Primary Examiner — Brett Miller*(74) Attorney, Agent, or Firm* — Boudwin Intellectual Property; Daniel Boudwin(57) **CLAIM**

The ornamental design for a food cutting tool, as shown and described.

DESCRIPTION

FIG. 1 shows a perspective view of a food cutting tool; FIG. 2 shows a front view of the food cutting tool; FIG. 3 shows a rear view of the food cutting tool; FIG. 4 shows a right side view of the food cutting tool; FIG. 5 shows a left side view of the food cutting tool; FIG. 6 shows a top plan view of the food cutting tool; and, FIG. 7 shows a bottom plan view of the food cutting tool. The shade lines in the Figures show contour and not surface ornamentation.

1 Claim, 3 Drawing Sheets(56)
